SETH WAY, OF LA PORTE, INDIANA.

Letters Patent No. 87,312, dated February 23, 1869.

IMPROVED CLOTHES-DRIER.

The Schedule referred to in these Letters Patent and making part of the same.

To all whom it may concern:

Be it known that I, SETH WAY, of La Porte, in the county of La Porte, and State of Indiana, have invented a new and useful Improvement in Clothes-Driers; and I do hereby declare that the following is a full, clear, and exact description of the same, reference being had to the annexed drawings, making part of this specification, in which—

My improvements relate to that class of clothes-driers which are attached to the pipe of a stove, and clothes dried by the heat arising from the stove; and the points on which I have made my improvements on former driers will appear from the claims, hereinafter to be set forth.

In the drawings—

A is the stove-pipe.

B, the collar, which is constructed of thin metal, the top edge of which is slit to any required depth, bent over at right angles with its surface, and pierced to receive the hook in the end of the bar; or a lip, b, may be formed in the surface for the same purpose.

The collar is clasped around the stove-pipe A, and made fast by the thumb-screw C.

D are arms attached to the collar B, by means of a long hook, c, on the top of the arms D, hooking into the top or centre of the collar B, at any point around said collar, and are kept in place and made steady by the shoe or fork e, on the under-side of the said arms D, upon which small clothes, stockings, handkerchiefs, and other articles are hung to dry.

I do not claim a clothes-drier in which the arms are pivoted to the collar; but

What I do claim, is—

1. A collar, B, of thin metal, slit and bent in the manner described, and clamped by thumb-screw C, as and for the purpose specified.

2. The arm D, provided with a hook, c, upon the top, and a shoe or fork, e, upon the bottom, as and for the purpose specified.

3. The combination of the collar B, and arm D, both as described, for the purpose specified.

In testimony whereof, I have signed my name to this specification, in the presence of two subscribing witnesses.

SETH WAY.
